(57) **ABSTRACT**

A two-stage driver supplies current to a light emitting diode (LED) load. The two-stage driver includes a first stage and a second stage. The first stage has a first flyback converter. The first stage is configured to receive a non-regulated voltage input and to generate a substantially constant bulk voltage across a first-stage output filter capacitor. The second stage has a second flyback converter. The second stage is configured to receive the bulk voltage from the first stage. The second stage is further configured to generate a desired current through the LED load. The second stage is electrically isolated from the first stage such that the LED load does not share a common ground reference with the non-regulated voltage input to the first stage.

LED DRIVER WITH DOUBLE FLYBACK TECHNOLOGY

RELATED APPLICATION

This application claims the benefit under 35 USC. § 119(e) of U.S. Provisional Application No. 63/238,403, filed Aug. 30, 2021, entitled "LED Driver with Double Flyback Topology," which is hereby incorporated by reference in its entirety.

FIELD OF THE INVENTION

The present disclosure relates generally to lighting systems and, more particularly, to apparatuses to control light emitting diodes (LEDs).

BACKGROUND

A conventional single-stage flyback converter provides a low-cost solution for a class II LED driver. The flyback converter has a low component count, provides a high power factor (PF), has a low third harmonic distortion (THD), and has an isolated output. Control logic within the converter senses the output current through a plurality of LEDs and regulates the output current by controlling a semiconductor switch in a switching circuit. The control logic controls the switching of the semiconductor switch to cause the output current to have a magnitude corresponding to a dimmer control input. Such a conventional single-stage flyback converter has drawbacks. For example, the converter is operable only over a narrow voltage range and a narrow current range. The converter has a high 120 Hz current ripple. The converter may be unstable in a low dimming range, which may cause flickering. The leakage inductance of a flyback transformer in the converter has to be tightly controlled to avoid high voltage overshoot across the switching semiconductor. The control logic has to provide isolation to transfer a feedback control signal from a secondary side to a primary side, which have isolated ground references. These drawbacks limit the application of the single-stage flyback topology in LED driver applications.

SUMMARY

A need exists for a driver for an LED-based lighting system based on flyback topology that eliminates or reduces the drawbacks of a conventional single-stage flyback converter.

One aspect of the embodiments disclosed herein is a driver for light emitting diodes (LEDs). The LED driver includes a first stage voltage generating circuit having a first flyback transformer. The first stage circuit generates a bulk voltage that is loosely controlled to a desired bulk voltage level. A second stage voltage generating circuit has a second flyback transformer. The second stage voltage generating circuit receives the bulk voltage and generates a controlled current to an LED load. The second stage voltage generating circuit tightly controls the current to the LED load. The second stage voltage generating circuit is electrically isolated from the first stage voltage generating circuit. No feedback is provided from the second stage voltage generating circuit to the second stage voltage generating circuit such that the first stage voltage generating circuit generates a substantially constant bulk voltage irrespective of the load current.

2

Another aspect of the embodiments disclosed herein is a two-stage driver that supplies current to a light emitting diode (LED) load. The two-stage driver includes a first stage and a second stage. The first stage has a first flyback converter. The first stage is configured to receive a non-regulated voltage input and to generate a substantially constant bulk voltage across a first-stage output filter capacitor. The second stage has a second flyback converter. The second stage is configured to receive the bulk voltage from the first stage. The second stage is further configured to generate a desired current through the LED load. The second stage is electrically isolated from the first stage such that the LED load does not share a common ground reference with the non-regulated voltage input to the first stage.

In certain embodiments in accordance with this aspect, the first flyback converter includes a first flyback transformer having a primary winding, a secondary winding and an auxiliary winding. A first electronic switch is selectively activated to enable current to flow through the primary winding of the first flyback transformer from the non-regulated voltage input to a primary circuit ground reference. The current flowing through the primary winding of the first flyback transformer induces a voltage on the secondary winding of the first flyback transformer that is applied to the first-stage output filter capacitor to produce the bulk voltage. A first switch controller controls the first electronic switch to selectively activate the first electronic switch. A primary voltage control circuit is coupled to the auxiliary winding of the first flyback transformer. The primary control circuit generates a first sensed voltage responsive to the bulk voltage across the secondary winding of the first flyback transformer. The first sensed voltage is applied to the first switch controller. The first switch controller is responsive to the sensed voltage to control the switching of the electronic switch to maintain the bulk voltage at a substantially constant magnitude.

In certain embodiments, the second flyback converter includes a second flyback transformer having a primary winding and a secondary winding. A second electronic switch is selectively activated to enable current to flow through the primary winding of the second flyback transformer from the first-stage output filter capacitor to a secondary circuit ground reference. The current flowing through the primary winding of the second flyback transformer induces a voltage on the secondary winding of the second flyback transformer that is rectified and applied to the LED load. A current sensor senses a magnitude of a load current flowing through the LED load and generates a sensed feedback signal responsive to the sensed magnitude of the load current. A switch controller applies a switching signal to the second electronic switch to selectively activate the second electronic switch. The switch controller is configured to receive the sensed feedback signal as a first input signal and to receive a dimmer control signal representing a desired magnitude of the load current as a second input signal. The switch controller is configured to compare the sensed feedback signal to the dimmer control signal and to modify the switching signal to maintain the sensed feedback signal at a magnitude determined by the dimmer control signal.

In certain embodiments, the second flyback converter further includes a voltage sensing circuit configured to sense the voltage applied to the LED load and to generate a sensed voltage signal. The sensed voltage signal is applied as a third input signal to the switch controller. The switch controller is further responsive to the sensed voltage signal to further modify the switching signal.

In certain embodiments, the primary voltage control circuit is configured to receive a standby command signal having an active mode and an inactive mode. The primary voltage control circuit is responsive to the standby command signal in the inactive mode to provide the first sensed voltage to the first switch controller at a first sensed voltage level. The first switch controller is responsive to the sensed voltage at the first sensed voltage level to control the switching of the electronic switch to maintain the bulk voltage at a first substantially constant magnitude. The primary voltage control circuit is responsive to the standby command signal in the active mode to provide the first sensed voltage to the first switch controller at a second sensed voltage level. The first switch controller is responsive to the sensed voltage at the second sensed voltage level to control the switching of the electronic switch to maintain the bulk voltage at a second substantially constant magnitude.

In certain embodiments in accordance with this aspect, the second flyback converter includes a flyback transformer having a primary winding and a secondary winding. An electronic switch is selectively activated to enable current to flow through the primary winding of the flyback transformer from the first-stage output filter capacitor to a secondary circuit ground reference. The current flowing through the primary winding of the flyback transformer induces a voltage on the secondary winding of the flyback transformer that is rectified and applied to the LED load. A current sensor senses a magnitude of a load current flowing through the LED load and generates a sensed feedback signal responsive to the sensed magnitude of the load current. A switch controller applies a switching signal to the electronic switch to selectively activate the electronic switch. The switch controller is configured to receive the sensed feedback signal as a first input signal and to receive a dimmer control signal representing a desired magnitude of the load current as a second input signal. The switch controller is configured to compare the sensed feedback signal to the dimmer control signal and to modify the switching signal to maintain the sensed feedback signal at a magnitude determined by the dimmer control signal.

In certain embodiments, the second flyback converter further includes a voltage sensing circuit configured to sense the voltage applied to the LED load and to generate a sensed voltage signal. The sensed voltage signal is applied as a third input signal to the switch controller. The switch controller is further responsive to the sensed voltage signal to further modify the switching signal.

Another aspect of the embodiments disclosed herein is a method of controlling the current through light emitting diodes (LEDs) comprising generating a bulk DC voltage from an input source using a first flyback converter stage having a first flyback transformer. The first flyback transformer has a first primary winding referenced to a first ground reference. The method further comprises converting the bulk DC voltage to a controlled current through the LEDs using a second flyback converter having a second flyback transformer. The second flyback transformer has a second primary winding referenced to a second ground reference. The second ground reference is electrically isolated from the first ground reference.

In certain embodiments in accordance with this aspect, the method further includes receiving a standby control signal in an inactive mode and generating the bulk DC voltage at a first magnitude; and receiving the standby control signal in an active mode and generating the DC voltage at a second magnitude, the second magnitude lower than the first magnitude.

BRIEF DESCRIPTIONS OF THE SEVERAL VIEWS OF THE DRAWINGS

FIG. 1 illustrates a circuit diagram of an exemplary single-stage flyback converter configured as an LED driver to drive an LED load.

FIG. 2 illustrates a circuit diagram of an LED driver having a buck converter interposed between the output of the single-stage flyback converter and the LED load.

FIG. 3 illustrates a circuit diagram of an improved LED driver having a non-isolated flyback converter interposed between the single-stage flyback converter and the LED load.

FIG. 4 illustrates a circuit diagram of a further improved LED driver corresponding to the improved LED driver of FIG. 3 and further including low standby power control.

DETAILED DESCRIPTION

The following detailed description of embodiments of the present disclosure refers to one or more drawings. Each drawing is provided by way of explanation of the present disclosure and is not a limitation. Those skilled in the art will understand that various modifications and variations can be made to the teachings of the present disclosure without departing from the scope of the disclosure. For instance, features illustrated or described as part of one embodiment can be used with another embodiment to yield a still further embodiment.

The present disclosure is intended to cover such modifications and variations as come within the scope of the appended claims and their equivalents. Other objects, features, and aspects of the present disclosure are disclosed in the following detailed description. One of ordinary skill in the art will understand that the present disclosure is a description of exemplary embodiments only and is not intended as limiting the broader aspects of the present disclosure.

FIG. 1 illustrates a conventional LED driver circuit 100 based on a flyback converter 102. The LED driver circuit includes a primary section 104 and a secondary section 106. The LED driver circuit provides current to an LED load 110. In the illustrated embodiment, the LED load comprises a plurality of LEDs (not shown) connected between a first LED load terminal 114 and a second LED load terminal 114. The load current flowing through the LEDs causes the LEDs to illuminate. In order to provide consistent illumination, the load current through the LEDs is maintained at a substantially constant magnitude. The illustrated driver circuit utilizes a secondary current sensing technique (described below) to control the secondary current.

An AC source 120 provides an AC input voltage to the LED driver circuit 100 via a first AC input line 122 and a second AC input line 124. In the illustrated embodiment, the AC input voltage may vary from 86 volts RMS to 265 volts RMS. The AC input voltage between the first AC input line and the second AC input line is applied between a first input terminal 132 and a second input terminal 134 of a full-wave bridge rectifier 130. The bridge rectifier has a first output terminal 136 and a second output terminal 138. A first rectifier diode 140 has an anode connected to the first input terminal and a cathode connected to the first output terminal. A second rectifier diode 142 has an anode connected to the second input terminal and a cathode connected to the first output terminal. A third rectifier diode 144 has an anode connected to the second output terminal and has a cathode connected to the first input terminal. A fourth rectifier diode

146 has an anode connected to the second output terminal and has a cathode connected to the second input terminal. The bridge rectifier operates in a conventional manner to produce a pulsating DC voltage on the first output terminal which is referenced to the second output terminal. The second output terminal is connected to a primary ground reference 150. An input filter capacitor 152 is connected between the first output terminal and the primary ground reference. The input filter capacitor smooths the pulsating DC voltage.

The first output terminal 136 of the bridge rectifier 130 is connected to a first terminal 164 of the primary winding 162 of a flyback transformer 160 in the flyback converter 102. The flyback transformer galvanically isolates the primary section 104 of the LED driver circuit 100 from the secondary section 106. The primary winding of the flyback transformer has a second terminal 166. The flyback transformer has a secondary winding 170, which has a first terminal 172 and a second terminal 174. The flyback transformer has an N:1 turns ratio between the primary winding and the secondary winding such that the voltage across the primary winding is N times the voltage across the secondary winding and such that the current through the secondary winding is N times the current through the primary winding. The flyback transformer may also have at least one auxiliary winding (not shown in FIG. 1).

The first terminal 172 of the secondary winding 170 of the flyback transformer 160 is connected to secondary ground reference 180. The secondary ground reference is electrically isolated from the primary ground reference 150 by the flyback transformer. The second terminal 174 of the secondary winding is connected to the anode of a secondary diode 182. The cathode of the secondary diode is connected to the first terminal 186 of a secondary filter capacitor 184. The secondary filter capacitor may also be referred to as an output filter capacitor. A second terminal 188 of the secondary filter capacitor is connected to the secondary ground reference and thus to the first terminal of the secondary winding of the flyback transformer. In one embodiment, the secondary filter capacitor has a capacitance of approximately 2,000 microfarads. The cathode of the secondary diode and the first terminal of the secondary filter capacitor are connected to a first output terminal 190 of the LED driver circuit 100, which is connected to the first terminal 114 of the LED load 110. The secondary ground reference is connected to a second output terminal 192 of the LED driver circuit via a secondary current sensing resistor 200. The second output terminal of the LED driver circuit is connected to the second terminal 114 of the LED load.

The second terminal 114 of the LED load 110 is connected to a first input 212 of an isolated control logic circuit 210. A second input 214 of the isolated control logic circuit receives a dimmer control input from a dimmer control source (not shown). The dimmer control input has a voltage corresponding to a desired current flow through the LED load. The current flowing through the current sensing resistor 200 generates a voltage across the current sensing resistor proportional to the magnitude of the current flowing through the LED load. The isolated control logic circuit compares the voltage across the current sensing resistor with the voltage of the dimmer control input and generates a feedback signal on an output terminal 216 responsive to the difference in the two voltages. The feedback signal on the output terminal of the isolated control logic circuit is isolated from the secondary ground reference 180 and is referenced to the primary ground reference 150. For

example, the isolated control logic circuit may include an optical isolator in an output circuit.

As further shown in FIG. 1, the second terminal 166 of the primary winding 162 of the flyback transformer 160 is connected to a first terminal 302 of a semiconductor switch 300. The switch further includes a second terminal 304 and a control (gate) terminal 306. For example, the semiconductor switch may comprise a metal oxide semiconductor field effect transistor (MOSFET) wherein the first terminal is the drain of the MOSFET, the second terminal is the source of the MOSFET, and the control terminal is the gate of the MOSFET. In the illustrated embodiment, the MOSFET is an N channel enhancement mode transistor, which is normally off (e.g., has a high impedance between the drain and the source). The MOSFET turns on to provide a low-impedance path (e.g., a few tens of milliohms) between the drain and the source when a sufficiently large voltage differential is applied between the gate and the source of the MOSFET. The second terminal (source) of the MOSFET is connected to the primary ground reference 150 via a primary current sensing resistor 308. When the MOSFET is turned on, a current flows from the first output terminal 136 of the bridge rectifier 130, through the primary winding 162 of the flyback transformer 160, through the MOSFET from the first terminal (drain) to the second terminal (source), and to the primary ground reference via the primary current sensing resistor. A voltage is developed across the primary current sensing resistor. The voltage is proportional to the current through the current flowing through the primary winding.

The control terminal (gate) 306 of the MOSFET 300 is controlled by a gate drive (GD) output terminal 322 of a switch controller integrated circuit (CNTRL IC) 320. In the illustrated embodiment, the switch controller IC comprises an L6562 transition-mode power factor correction (PFC) controller, which is commercially available from STMicroelectronics of Geneva, Switzerland. The switch controller IC receives a feedback voltage via a voltage feedback (VF) input terminal 324, which is connected to receive the feedback voltage from the output terminal of the isolated control logic circuit 210 in the secondary section 104. Thus, the switch controller IC receives a voltage responsive to the difference between the instantaneous LED load current flowing through the current sensing resistor 200 and the desired LED load current. The switch controller IC further includes a current sense (ISEN) input terminal 326, which receives the voltage generated across the primary current sensing resistor 308. The voltage is proportional to the current through the primary winding 162 of the flyback transformer 160. The switch controller IC monitors this current sensing voltage internally to determine when to switch off the gate drive signal on the gate drive (GD) output terminal 322. The illustrated switch controller IC includes additional inputs (e.g., power input and compensation inputs), which are not shown in FIG. 1.

The switch controller IC 320 operates in a conventional manner to output a high output signal on the gate drive (GD) output terminal 322 to turn on the MOSFET 300 to cause current to flow through the primary winding 162 of the flyback transformer 160 from the first terminal 164 to the second terminal 166 of the primary winding. The switch controller IC outputs a low output signal on the gate control output terminal to turn off the MOSFET to stop current flow through the primary winding of the transformer. The time varying current flowing through the primary winding generates current flow in the secondary winding 170, which is rectified by the secondary diode 182 and which is applied to the secondary filter capacitor 184 to thereby charge the

secondary filter capacitor. The voltage across the secondary filter capacitor is applied to the LED load 110 to cause an output current to flow through the load.

The output current flowing through the LED load 110 is sensed by the secondary current sensing resistor 200. The voltage representing the sensed current is compared to the voltage of the dimmer control input signal to produce the feedback signal, which is applied to the voltage feedback input (VF) of the switch controller IC 320, as described above. The switch controller IC is responsive to the feedback signal to switch the MOSFET 300 on and off with varying durations to adjust the voltage across the secondary filter capacitor to a magnitude sufficient to cause the current flowing through the LED load to have a desired magnitude (e.g., 180 milliamps in one example). Note that although the operation of the switch controller IC determines the voltage across the secondary filter capacitor, the actual voltage across the LED load required to maintain the desired current through the LED load varies with the characteristics of the LEDs within the LED load and also varies with other factors such as, for example, temperature. Thus, it should be understood that the sensed output current through the LED load is the controlled parameter. The secondary voltage across the LED load may vary to maintain the sensed current magnitude at or near the desired output current magnitude (e.g., at approximately 180 milliamperes in certain embodiments).

As discussed above, the conventional LED driver circuit 100 illustrated in FIG. 1 has a number of drawbacks. For example, the converter is operable only over a narrow voltage range and a narrow current range. The converter has a high 120 Hz current ripple. The converter may be unstable in a low dimming range which may cause flickering. The leakage inductance of a flyback transformer in the converter has to be tightly controlled to avoid high voltage overshoot across the switching semiconductor. The control logic has to provide isolation to transfer a feedback control signal from a secondary side to a primary side which have isolated ground references. These drawbacks limit the application of the single-stage flyback topology in LED driver applications.

FIG. 2 illustrates an LED driver circuit 400, which includes a modified flyback converter 402 in a modified primary section 404, and which includes a modified secondary section 406. The LED driver circuit of FIG. 2 includes elements corresponding to the elements of the LED driver circuit 100, and like elements are identified with the corresponding reference numbers.

In the improved LED driver circuit 400 of FIG. 2, the modified secondary section 406 includes a buck converter 410 connected between the first output terminal 190 and a buck converter output terminal 412. The first terminal 112 of the LED load 110 is not connected to the first output terminal as in FIG. 1. Rather, the first terminal of the LED load is connected to the buck converter output terminal 412.

The buck converter 410 includes a second MOSFET 420, which has a first (drain) terminal 422 connected to the anode of the secondary diode 182 and to the first terminal 186 of the secondary filter capacitor 184 at the first output terminal 190. The second MOSFET has a second (source) terminal 424 connected to an internal buck converter node 430. The second MOSFET has a gate terminal 426 connected to an output terminal 442 of a gate driver circuit 440. The gate driver circuit has an input terminal 444 connected to an output terminal 452 of a control logic circuit 450. The control logic circuit has a first input terminal 454 and a second input terminal 456. The first input terminal of the control logic circuit is connected to the second terminal 114

of the LED load 110. Thus, the voltage developed across the second current sensing resistor 200 is applied to the first input terminal of the control logic circuit. The second input terminal of the control logic circuit receives the dimmer control input voltage. The control logic circuit generates an internal voltage responsive to a difference between the voltage representing the sensed current and the voltage representing a desired LED current. The control logic circuit generates an output signal on the output terminal 452 to selectively turn the second MOSFET on and off via the gate driver circuit. The output signal is varied to maintain the current through the LED load approximately equal to the desired current represented by the dimmer control input.

The buck converter 410 includes a buck converter diode 460. The buck converter diode has an anode connected to the secondary ground reference 180 and has a cathode connected to the second (source) terminal 424 of the second MOSFET 420 at the internal buck converter node 430.

The buck converter 410 includes a buck converter inductor 470 having a first terminal 472 connected to the second (source) terminal 424 of the second MOSFET 420 at the internal buck converter node 430. The buck converter inductor has a second terminal 474 connected to the buck converter output terminal 412 and thus connected to the first terminal 112 of the LED load 110.

The buck converter 410 includes a buck converter filter capacitor 480 having a first terminal 482 connected to the buck converter output terminal 412 and having a second terminal 484 connected to the secondary ground reference 180 via the second output terminal 192.

The buck converter 410 includes a first buck converter output voltage sensing resistor 490 and a second buck converter output voltage sensing resistor 492, which are connected in series between the buck converter output terminal 412 and the second output terminal 192. A first sensing node 494 connecting the two output voltage sensing resistors provides a first sensed output voltage proportional to the voltage across the LED load 110.

The LED driver circuit 400 further includes a flyback converter output voltage sensing resistor 500 and a second flyback converter output voltage sensing resistor 502, which are connected in series between the first output terminal 190 and the second output terminal 192 of the modified flyback converter 402. A second sensing node 504 connecting the two input voltage sensing resistors provides a second sensed output voltage proportional to the voltage on the first output terminal and thus proportional to the voltage applied to the input of the buck converter 410. The voltage on the first output terminal may be referred to as the bulk voltage provided by the modified flyback converter. Since the second stage buck converter 410 controls the voltage across the LED load 110 to thereby control the load current, the first stage modified flyback converter of FIG. 2 does not have to control the bulk voltage as tightly as in the conventional embodiment of FIG. 1.

The first sensed output voltage from the first sensing node 494 is connected to a first input terminal 512 of an isolated control logic circuit 510. The second sensed output voltage from the second sensing node 504 is connected to a second input terminal 514 of the isolated control logic circuit. The isolated control logic circuit generates a feedback signal on an output terminal 516 responsive to a difference between the two voltages and applies the feedback signal to the voltage feedback (VF) input terminal 324 of the switch controller IC 320. The switch controller IC is responsive to the feedback signal to adjust the switching signal applied to the MOSFET 300 to reduce any difference between the two

sensed output voltages. The isolated control logic circuit includes optical isolation or other isolation circuitry coupled to the output terminal to allow the feedback signal generated in the secondary section 104 to control the switch controller IC in the primary section 102.

In the LED driver 400 of FIG. 2, the first stage modified flyback converter 402 provides the bulk voltage across the secondary filter capacitor 184. The switch controller IC 320 controls the flyback converter circuit to provide a high power factor (PF) and a low third harmonic distortion (THD). The buck converter 410 regulates the output current through the LED load 110 tightly in response to the dimmer control signal received on the second input terminal 456 of the control logic 450. The LED driver circuit of FIG. 2 operates over a wide range of load voltages and load currents, has a low 120 Hz ripple and provides a stable current at low dimming levels.

The embodiment of FIG. 2 has drawbacks. For example, the buck converter 410 accepts a limited input voltage of around 60 volts. This requires a large turns ratio of primary turns (N_p) to secondary turns N_s in a range of 3-5 (i.e., N_p/N_s varies from 3 to 5). The large turns ratio causes difficulty in reducing the leakage inductance of the transformer, which increases the manufacturing cost of the transformer.

Another drawback is caused by the second MOSFET 420. The drain terminal 422 and the source terminal 424 of the second MOSFET are floating at voltage levels that are not referenced to the second ground reference 180. Thus, the gate driver 440 is a high side gate driver that provides a high voltage gate driving signal to turn the second MOSFET on and off. Such high side gate drivers are very expensive and cause an increase in the cost of the LED driver 400.

Another drawback is caused by the positioning of the second MOSFET 420 between the first output terminal 190 of the switching converter 402 and the LED load 110. Underwriters Laboratories (UL) requires that lighting circuits pass a fault test such that if the second MOSFET is shorted, the output voltage across the LED load must remain less than 60 volts and the current through the LED load cannot exceed 8 amperes. Additional components (not shown) may be needed to assure that the maximum voltage and the maximum current are not exceeded.

FIG. 3 illustrates an LED driver 600 that avoids the drawbacks of the LED driver 400 of FIG. 2. The LED driver of FIG. 3 includes a modified flyback converter 602 in a further modified primary section 604. The LED driver of FIG. 3 further includes a further modified secondary section 606. The LED driver circuit of FIG. 3 includes elements corresponding to the elements of the LED driver circuit 100, and like elements are identified with the corresponding reference numbers.

In the LED driver 600 of FIG. 3, the further modified secondary section 606 does not include a buck converter. Rather, the buck converter 410 of FIG. 2 is replaced with a non-isolated secondary stage flyback converter 610 connected between the first output terminal 190 of the modified flyback converter 602 and the LED load 110. The secondary stage flyback converter includes a second flyback transformer 620 having a primary winding 622 and a secondary winding 624. A first terminal 630 of the primary winding of the second flyback transformer is connected to the first output terminal 190 of the modified flyback converter 602. A second terminal of the primary winding of the second flyback transformer is connected to a first (drain) terminal 642 of a second MOSFET 640. A second (source) terminal 644 of the second MOSFET is connected to the second

output terminal 192 of the further modified flyback converter and is thus connected to the secondary ground reference 180. A gate terminal 646 of the second MOSFET is connected to an output terminal 652 of a control logic circuit 650. The control logic circuit has a first input terminal 654, which is connected to receive the dimmer control input signal. The control logic circuit has a second input terminal 656 connected to the second terminal 114 of the LED load 110 and thus connected to receive the voltage developed across the current sensing resistor 200, which is proportional to the current through the LED load. The control logic circuit has a third input terminal 658. The connection to the third input terminal of the control logic circuit is described below.

The secondary winding 624 of the second flyback transformer 620 has a first terminal 660 and a second terminal 662. The first terminal is connected to the secondary ground reference 180. The second terminal is connected to an anode of a secondary flyback converter diode 670. A cathode of the secondary flyback converter diode is connected to an output terminal 672 of the secondary stage flyback converter 610. A secondary flyback converter filter capacitor 680 has a first terminal 682 connected to the output terminal of the secondary stage flyback converter and has a second terminal 684 connected to the secondary ground reference.

A first secondary voltage sensing resistor 690 and a second secondary voltage sensing resistor 692 are connected in series between the output terminal 672 of the secondary stage flyback converter 610 and the secondary ground reference 180. The two voltage sensing resistors are connected at a secondary voltage sensing node 694. The two voltage sensing resistors are connected as a voltage divider circuit such that the voltage on the secondary voltage sensing node is proportional to the voltage between the output terminal of the secondary stage flyback converter and the secondary ground reference. The secondary voltage sensing node is connected to the third terminal 658 of the control logic circuit 650.

The control logic circuit 650 receives the voltage across the output current sensing resistor 200 on the second input terminal 656 and receives the voltage representing the desired current on the first input terminal 654. The control logic circuit compares the two voltages and regulates the switching of the second MOSFET 640 to adjust the output current to correspond to the desired current. The control logic circuit also receives the voltage proportional to the output voltage on the third input terminal 658 and adjusts the switching of the second MOSFET to maintain the output voltage within a desired voltage range.

The LED driver 600 of FIG. 3 has a number of advantages. The primary winding 622 and the secondary winding 624 of the second flyback transformer 620 have respective terminals connected to the secondary ground reference 180. The source terminal 646 of the second MOSFET 640 is connected to the secondary ground reference, and the control logic circuit 650 is also connected to the secondary ground reference. Thus, the secondary flyback transformer is not electrically isolated, which allows the gate drive circuitry to be much simpler than the floating gate drive circuitry in the LED driver 400 of FIG. 2.

The LED load 100 is not electrically isolated from the primary winding 622 of the second flyback transformer 620 because the secondary winding 624 and the primary winding are connected to the common secondary ground reference 180. However, electrical isolation of the LED load from the primary winding of the secondary flyback transformer is not necessary because the flyback transformer 160 in the modified flyback converter 602 provides electrical isolation

11

between the modified primary section **604** and the modified secondary section **606** and thus isolates the LED load from the modified primary section. The LED load in FIG. 3 is not in the main power path from the secondary filter capacitor **184**. Thus, even if the second MOSFET **640** is shorted, no large currents will flow through the LED load and no large voltage will appear across the LED load because the secondary flyback transformer provides power isolation between the secondary filter capacitor and the LED load. Accordingly, no additional control circuitry is needed to handle a short across the second MOSFET. This simplifies the design of the LED driver and reduces the cost.

The current through the LED load **110** is tightly controlled by the secondary stage flyback converter **610**. Thus, the output of the modified first stage flyback converter **602** on the first output terminal **190** applied across the secondary filter capacitor **184** does not have to be tightly controlled. Accordingly, the LED driver **600** of FIG. 3 does not have any feedback from the further modified secondary section **606** to the further modified primary section **604**. Instead, the further modified primary section includes a simple primary voltage control circuit **700** comprising an auxiliary winding **710** forming part of the isolated flyback transformer **160**. A first terminal **712** of the auxiliary winding is connected to the primary ground reference **150**. A second terminal **714** of the auxiliary winding is connected to an anode of a power supply diode **720**. A cathode of the power supply diode is connected to a voltage output node **722**. A first terminal **732** of a power supply filter capacitor **730** to the voltage output node. A second terminal **734** of the power supply filter capacitor is connected to the primary ground reference **150**. A first power supply voltage sensing resistor **740** and a second power supply voltage sensing resistor **742** are connected in series between the voltage output node and the primary ground reference. The two power supply voltage sensing resistors are connected at a power supply voltage sensing node **744**. The power supply voltage sensing node is connected to the voltage feedback (VF) input terminal **324** of the switch controller IC **320**.

The voltage control circuit **700** operates as a simple power supply that rectifies a voltage developed across the auxiliary winding **710** and produces a rectified voltage across the power supply filter capacitor **730**. A voltage proportional to the rectified voltage is produced on the power supply sensing node **744** and is thus applied to the voltage feedback (VF) input terminal **324** of the switch controller IC **320**. The switch controller IC is responsive to the sensed voltage to vary the drive signals applied to the MOSFET **300** to maintain the sensed voltage at a substantially constant voltage determined by an internal reference voltage V_{REF} within the switch controller IC. The voltage developed across the auxiliary winding is proportional to the voltage across the secondary winding. Accordingly, a voltage V_{CSEC} developed across the secondary filter capacitor **184** has the following relationship to the reference voltage within the switch controller IC:

$$V_{CSEC} = N_{SA} \times V_{REF} \left(\frac{R_{740} + R_{742}}{R_{742}} \right) \quad (1)$$

In Equation (1), R_{740} is the resistance of the first power supply voltage sensing resistor **740** and R_{742} is the resistance of the second power supply voltage sensing resistor **742**. In Equation (2), N_{SA} is the turns ratio of the number N_S of

12

secondary turns to the number NA of auxiliary turns of the isolated flyback transformer **160** of FIG. 3.

As illustrated in FIG. 3, no feedback is required from the secondary section **604** to the primary section **606** to control the magnitude of the bulk voltage generated by the modified flyback converter **602** in the primary section. Accordingly, no isolated feedback circuitry is required, which reduces the complexity and cost of the LED driver **600**.

Since the further modified secondary section **606** uses the flyback converter **610** with the non-isolated second flyback transformer **620**, the turns ratio between the primary winding **622** and the secondary winding **624** of the second flyback transformer is selected to minimize the current through the second MOSFET **640** and the primary winding. The lower current allows the second MOSFET to operate with a moderate drain-to-source on-resistance and also allows the use of smaller wire in the second flyback transformer. Both advantages reduce the cost of the LED driver **600**.

The ability to select the turns ratio for the non-isolated second flyback transformer **620** allows the bulk voltage generated by the first flyback transformer **160** and applied across the secondary filter capacitor **184** to be increased. For example, for a 55-watt LED driver **600** having a bulk voltage across the secondary filter capacitor of approximately 60 volts, the secondary filter capacitor should have a capacitance of at least 470 microfarads to control the 120 Hz voltage ripple within a certain range (e.g., $\pm 10\%$). Increasing the turns ratio of the second flyback transformer allows the bulk voltage across the secondary filter capacitor to be increased to 200 volts. The energy E stored in the secondary filter capacitor is determined as $E = \frac{1}{2}CV^2$, wherein C is the capacitance of the secondary filter capacitor and V is the bulk voltage across the secondary filter capacitor. By increasing the bulk voltage to 200 volts, the capacitance of the secondary filter capacitor can be decreased to 47 microfarads. A 47-microfarad electrolytic capacitor at 200 volts has a much small cost and size than a 470-microfarad capacitor at a lower voltage.

Increasing the bulk voltage on the secondary filter capacitor **184** has a further benefit of allowing the turns ratio between the primary winding **162** and the secondary winding **170** of the first flyback transformer **160** to be 1:1. The 1:1 turns ratio permits the use of bifilar wire to wind the primary winding and the secondary winding together in a single operation. The bifilar winding simplifies the manufacturing process and substantially reduces the leakage inductance of the primary winding. The reduced leakage inductance improves the efficiency of the primary section **604** and substantially reduces voltage ringing on the first MOSFET **300** when the first MOSFET is turned off. The reduced voltage ringing improves the electromagnetic interference (EMI) of the LED driver **600**.

FIG. 4 illustrates an LED driver **800**, which is a modification of the LED driver **600** of FIG. 3. The LED driver of FIG. 4 reduces power consumption when the dimmer control input is reduced to a dim level or to a level where the current through the LED load is turned off. The elements of the LED driver of FIG. 4 are labeled with the same reference numbers as the corresponding elements of the LED driver of FIG. 3 and operate in corresponding manners.

The LED driver **800** of FIG. 4 includes a further modified primary flyback converter **802** in a primary section **804**. A secondary section **806** includes a modified secondary flyback converter **810**. The modified secondary flyback converter of FIG. 4 includes a modified control logic circuit **850** in place of the control logic circuit **650** of FIG. 3. The

13

modified control logic circuit includes the first input terminal **654**, the second input terminal **656** and the third input terminal **658**, which are connected as described above. The modified control logic circuit also includes the output terminal **652**, which is connected to the gate terminal **646** of the second MOSFET **640** as described above. The output terminal **652** is referred to as the “first” output terminal of the modified control logic circuit.

The modified control logic circuit **850** of FIG. 4 also includes a second output terminal **860**. The second output terminal of the modified control logic circuit is connected via a current limiting resistor **862** to a first input terminal **872** of an optical isolator **870** and is thus connected to the anode of a light emitting diode (LED) **874** within the optical isolator. The cathode of the LED is connected to the secondary ground reference **180** via a second input terminal **876** of the optical isolator. A phototransistor **880** within the optical isolator has a collector connected to a first output terminal **882** and has an emitter connected to a second output terminal **884**.

The first output terminal **882** of the optical isolator **870** is connected to the voltage output node **722** of the primary voltage control circuit **700**. The second output terminal **884** of the optical isolator is connected to a first terminal **892** of a third power supply voltage sensing resistor **890**. A second terminal **894** of the third power supply voltage sensing resistor is connected to the power supply sensing node **744**. As connected, when the phototransistor **880** within the optical isolator is conducting, the third power supply voltage sensing resistor **890** is electrically connected in parallel with the first power supply voltage sensing resistor **740** between the voltage output node **722** to the power supply sensing node **744**. When the phototransistor is not conducting the third power supply voltage sensing resistor is effectively disconnected.

The modified control logic circuit **850** operates as described above to receive the voltage inputs on the first input terminal **654**, the second input terminal **656** and the third input terminal **658** and to control the first output terminal **652** in response to the voltage inputs. The modified control logic circuit further monitors the voltage of the dimmer control input on the first input terminal to determine when the voltage corresponds to a low dimming level or an off state. When the modified control logic circuit detects a low dimming level or an off state, the modified control logic circuit generates a high logic level on the second output terminal **860** to provide current through the current limiting resistor **862** to turn on the LED **874** within the optical isolator **870**. As described below, this high logic level signal is an active standby mode signal. Light emitted by the LED causes the phototransistor **880** to conduct, which causes the third power supply voltage sensing resistor **890** to be connected electrically in parallel with the first power voltage sensing resistor **740** between the voltage output node **722** to the power supply sensing node **744**. The lower parallel resistance of the two resistors cause the voltage across the second power supply voltage sensing resistor to be a greater proportion of the voltage on the voltage output node. The switch controller IC **320** adjusts the gate driver signals applied to the gate terminal **306** of the MOSFET **300** to lower the voltage across the transformer windings such that the voltage applied to the secondary filter capacitor **184** is reduced to a standby voltage $V_{STANDBY}$. The reduced voltage reduces the power consumption of the overall LED driver **800**. For example, the standby power can be reduced to less than 500 milliwatts. The foregoing can be understood from the following Equation (2), which corresponds to Equation

14

(1) with a resistance R_{890} of the third power supply voltage sensing resistor incorporated into the equation:

$$V_{STANDBY} = N_{SA} \times V_{REF} \left(\frac{\frac{R_{740} \times R_{890}}{R_{740} + R_{890}} + R_{742}}{R_{742}} \right) \quad (2)$$

As illustrated in Equation (2), the bulk voltage generated by the modified primary flyback converter **602** in the standby mode is a second substantially constant voltage that is not affected by the load current through the LED load **110** or the voltage across the LED load. Thus, the modified flyback converter does not receive any feedback from the modified secondary flyback converter **810**. Rather, the signal on the second output terminal **860** is a simple mode control signal. When the signal is high, the modified primary flyback converter is in standby mode and generates the lower bulk voltage. When the signal is low (e.g., the standby mode signal is inactive), the modified flyback converter generates the normal bulk voltage.

FIGS. 3 and 4 illustrate two versions of a double flyback technology for LED drivers. In the LED driver **600** and the LED driver **800**, the secondary flyback converter **610** is a non-isolated topology, which allows ground reference sharing between the switch **640** and the LED load **110**. This simplifies the control and gate drive designs. The secondary flyback converter electrically positions the LED load outside of the power path of the output of the primary flyback converter **602** as applied to the secondary filter capacitor **184**. Thus, the LED load is power isolated with respect to the secondary filter capacitor, which provides immunity from the effects of a short circuit of the of the second MOSFET **640**. The topologies of the LED drivers of FIGS. 3 and 4 allow the second flyback transformer **620** to have a higher primary-to-secondary turns ratio, which allows the bulk voltage on the secondary filter capacitor **184** to be higher. The higher voltage allows the secondary filter capacitor to have a lower capacitance, which permits a smaller and less expensive electrolytic capacitor to be used. The higher turns ratio of the second flyback transformer allows the first flyback transformer **160** to have a 1:1 turns ratio, which allows the use of bifilar windings and which helps to reduce the leakage inductance, power loss and voltage ringing on the first MOSFET **300**. In the embodiment of FIG. 4, a low standby power consumption is achieved by controlling the bulk voltage to a lower level when the dimming control input is set to an off state.

The previous detailed description has been provided for the purposes of illustration and description. Thus, although there have been described particular embodiments of a new and useful invention, it is not intended that such references be construed as limitations upon the scope of this invention except as set forth in the following claims.

What is claimed is:

1. A two-stage driver for supplying current to a light emitting diode (LED) load, the two-stage driver comprising:
  - a first stage having a first flyback converter, the first stage configured to receive a non-regulated voltage input and to generate a substantially constant bulk voltage across a first-stage output filter capacitor; and
  - an electrically isolated second stage having a second flyback converter, the second stage configured to receive the bulk voltage from the first stage, the second stage further configured to generate a desired current through the LED load,

15

wherein the first flyback converter includes:

- a first flyback transformer having a primary winding, a secondary winding and an auxiliary winding;
- a first electronic switch that is selectively activated to enable current to flow through the primary winding of the first flyback transformer from the non-regulated voltage input to a primary circuit ground reference, the current flowing through the primary winding of the first flyback transformer inducing a voltage on the secondary winding of the first flyback transformer that is applied to the first-stage output filter capacitor to produce the bulk voltage;
- a first switch controller that controls the first electronic switch to selectively activate the first electronic switch; and
- a primary voltage control circuit coupled to the auxiliary winding of the first flyback transformer, the primary control circuit generating a first sensed voltage responsive to the bulk voltage across the secondary winding of the first flyback transformer, the first sensed voltage applied to the first switch controller, the first switch controller responsive to the sensed voltage to control the switching of the electronic switch to maintain the bulk voltage at a substantially constant magnitude.

2. The two-stage driver as defined in claim 1, wherein the second flyback converter includes:

- a second flyback transformer having a primary winding and a secondary winding;
- a second electronic switch that is selectively activated to enable current to flow through the primary winding of the second flyback transformer from the first-stage output filter capacitor to a secondary circuit ground reference, the current flowing through the primary winding of the second flyback transformer inducing a voltage on the secondary winding of the second flyback transformer that is rectified and applied to the LED load;

a current sensor that senses a magnitude of a load current flowing through the LED load and that generates a sensed feedback signal responsive to the sensed magnitude of the load current; and

a switch controller that applies a switching signal to the second electronic switch to selectively activate the second electronic switch, the switch controller configured to receive the sensed feedback signal as a first input signal and to receive a dimmer control signal representing a desired magnitude of the load current as a second input signal, the switch controller configured to compare the sensed feedback signal to the dimmer control signal and to modify the switching signal to maintain the sensed feedback signal at a magnitude determined by the dimmer control signal.

3. The two-stage driver as defined in claim 2, wherein the second flyback converter further includes a voltage sensing circuit configured to sense the voltage applied to the LED load and to generate a sensed voltage signal, the sensed voltage signal applied as a third input signal to the switch controller, the switch controller further responsive to the sensed voltage signal to further modify the switching signal.

4. The two-stage driver as defined in claim 1, wherein the primary voltage control circuit is configured to receive a standby command signal having an active mode and an inactive mode, the primary voltage control circuit responsive to the standby command signal in the inactive mode to provide the first sensed voltage to the first switch controller at a first sensed voltage level, the first switch controller

16

responsive to the sensed voltage at the first sensed voltage level to control the switching of the electronic switch to maintain the bulk voltage at a first substantially constant magnitude, the primary voltage control circuit responsive to the standby command signal in the active mode to provide the first sensed voltage to the first switch controller at a second sensed voltage level, the first switch controller responsive to the sensed voltage at the second sensed voltage level to control the switching of the electronic switch to maintain the bulk voltage at a second substantially constant magnitude.

5. The two-stage driver as defined in claim 1, wherein the second flyback converter includes:

- a flyback transformer having a primary winding and a secondary winding;
- an electronic switch that is selectively activated to enable current to flow through the primary winding of the flyback transformer from the first-stage output filter capacitor to a secondary circuit ground reference, the current flowing through the primary winding of the flyback transformer inducing a voltage on the secondary winding of the flyback transformer that is rectified and applied to the LED load;

a current sensor that senses a magnitude of a load current flowing through the LED load and that generates a sensed feedback signal responsive to the sensed magnitude of the load current; and

a switch controller that applies a switching signal to the electronic switch to selectively activate the electronic switch, the switch controller configured to receive the sensed feedback signal as a first input signal and to receive a dimmer control signal representing a desired magnitude of the load current as a second input signal, the switch controller configured to compare the sensed feedback signal to the dimmer control signal and to modify the switching signal to maintain the sensed feedback signal at a magnitude determined by the dimmer control signal.

6. The two-stage driver as defined in claim 5, wherein the second flyback converter further includes a voltage sensing circuit configured to sense the voltage applied to the LED load and to generate a sensed voltage signal, the sensed voltage signal applied as a third input signal to the switch controller, the switch controller further responsive to the sensed voltage signal to further modify the switching signal.

7. A method of controlling the current through light emitting diodes (LEDs) comprising:

- generating a bulk DC voltage from an input source using a first flyback converter stage having a first flyback transformer, the first flyback transformer having a first primary winding referenced to a first ground reference; converting the bulk DC voltage to a controlled current through the LEDs using a second flyback converter having a second flyback transformer, the second flyback transformer having a second primary winding referenced to a second ground reference, the second ground reference electrically isolated from the first ground reference;

wherein upon receiving a standby control signal in an inactive mode, the bulk DC voltage is generated at a first magnitude; and

wherein upon receiving the standby control signal in an active mode the bulk DC voltage is generated at a second magnitude, the second magnitude lower than the first magnitude.

8. A two-stage driver for supplying current to a light emitting diode (LED) load, the two-stage driver comprising:

17

a first stage having a first flyback converter, the first stage configured to receive a non-regulated voltage input and to generate a substantially constant bulk voltage across a first-stage output filter capacitor; and
 an electrically isolated second stage having a second flyback converter, the second stage configured to receive the bulk voltage from the first stage, the second stage further configured to generate a desired current through the LED load,
 wherein the second flyback converter includes:
 a flyback transformer having a primary winding and a secondary winding;
 an electronic switch that is selectively activated to enable current to flow through the primary winding of the flyback transformer from the first-stage output filter capacitor to a secondary circuit ground reference, the current flowing through the primary winding of the flyback transformer inducing a voltage on the secondary winding of the flyback transformer that is rectified and applied to the LED load;
 a current sensor that senses a magnitude of a load current flowing through the LED load and that generates a sensed feedback signal responsive to the sensed magnitude of the load current; and
 a switch controller that applies a switching signal to the electronic switch to selectively activate the electronic switch, the switch controller configured to receive the sensed feedback signal as a first input signal and to receive a dimmer control signal representing a desired magnitude of the load current as a second input signal, the switch controller configured to compare the sensed feedback signal to the dimmer control signal and to modify the switching signal to maintain the sensed feedback signal at a magnitude determined by the dimmer control signal.

9. The two-stage driver of claim 8, wherein the first flyback converter includes:

a first flyback transformer having a primary winding, a secondary winding and an auxiliary winding;
 a first electronic switch that is selectively activated to enable current to flow through the primary winding of the first flyback transformer from the non-regulated voltage input to a primary circuit ground reference, the current flowing through the primary winding of the first flyback transformer inducing a voltage on the secondary winding of the first flyback transformer that is applied to the first-stage output filter capacitor to produce the bulk voltage;
 a first switch controller that controls the first electronic switch to selectively activate the first electronic switch; and
 a primary voltage control circuit coupled to the auxiliary winding of the first flyback transformer, the primary control circuit generating a first sensed voltage responsive to the bulk voltage across the secondary winding of the first flyback transformer, the first sensed voltage applied to the first switch controller, the first switch controller responsive to the sensed voltage to control the switching of the electronic switch to maintain the bulk voltage at a substantially constant magnitude.

18

10. The two-stage driver of claim 9, wherein the second flyback converter includes:
 a second flyback transformer having a primary winding and a secondary winding;
 a second electronic switch that is selectively activated to enable current to flow through the primary winding of the second flyback transformer from the first-stage output filter capacitor to a secondary circuit ground reference, the current flowing through the primary winding of the second flyback transformer inducing a voltage on the secondary winding of the second flyback transformer that is rectified and applied to the LED load;
 a current sensor that senses a magnitude of a load current flowing through the LED load and that generates a sensed feedback signal responsive to the sensed magnitude of the load current; and
 a switch controller that applies a switching signal to the second electronic switch to selectively activate the second electronic switch, the switch controller configured to receive the sensed feedback signal as a first input signal and to receive a dimmer control signal representing a desired magnitude of the load current as a second input signal, the switch controller configured to compare the sensed feedback signal to the dimmer control signal and to modify the switching signal to maintain the sensed feedback signal at a magnitude determined by the dimmer control signal.

11. The two-stage driver of claim 10, wherein the second flyback converter further includes a voltage sensing circuit configured to sense the voltage applied to the LED load and to generate a sensed voltage signal, the sensed voltage signal applied as a third input signal to the switch controller, the switch controller further responsive to the sensed voltage signal to further modify the switching signal.

12. The two-stage driver of claim 9, wherein the primary voltage control circuit is configured to receive a standby command signal having an active mode and an inactive mode, the primary voltage control circuit responsive to the standby command signal in the inactive mode to provide the first sensed voltage to the first switch controller at a first sensed voltage level, the first switch controller responsive to the sensed voltage at the first sensed voltage level to control the switching of the electronic switch to maintain the bulk voltage at a first substantially constant magnitude, the primary voltage control circuit responsive to the standby command signal in the active mode to provide the first sensed voltage to the first switch controller at a second sensed voltage level, the first switch controller responsive to the sensed voltage at the second sensed voltage level to control the switching of the electronic switch to maintain the bulk voltage at a second substantially constant magnitude.

13. The two-stage driver of claim 8, wherein the second flyback converter further includes a voltage sensing circuit configured to sense the voltage applied to the LED load and to generate a sensed voltage signal, the sensed voltage signal applied as a third input signal to the switch controller, the switch controller further responsive to the sensed voltage signal to further modify the switching signal.
